CLAIM

The ornamental design for a frame for a terminal tractor having a front and rear attachment device, as shown and described.

DESCRIPTION

FIG. 1 is a front perspective view of a frame for a terminal tractor having a front and rear attachment device, showing our new design.

FIG. 2 is a rear perspective view of the frame of FIG. 1.

FIG. 3 is a front view of the frame of FIG. 1.

FIG. 4 is a rear view of the frame of FIG. 1.

FIG. 5 is a right side view of the frame of FIG. 1.

FIG. 6 is a top view of the frame of FIG. 1.

FIG. 7 is a front perspective view of a front bumper isolated from the frame of FIG. 1.

FIG. 8 is a rear perspective view of the front bumper of FIG. 7.

FIG. 9 is a side view of the front bumper of FIG. 7.

FIG. 10 is a rear perspective view of a rear bumper isolated from the frame of FIG. 1; and,

FIG. 11 is a side view of the rear bumper of FIG. 10.

Any broken lines in the figures form no part of the claimed design.

1 Claim, 10 Drawing Sheets
